SELF-LUBRICATING PUMP

Herbert R. Lafferty, Davenport, Iowa, assignor to
Red Jacket Mfg. Co., Davenport, Iowa, a corpora-
tion of Iowa

Application November 30, 1931, Serial No. 577,875

1 Claim. (Cl. 308—121)

This invention relates to improvements in hydraulic pumps, and more particularly to reciprocating water pumps, and has for its principal object to produce a simple and economical construction whereby the water which passes through the pump is utilized to lubricate the main moving parts of the pump, thereby eliminating the necessity of using oil or other lubricant.

As heretofore constructed, reciprocating water pumps such as used with domestic pumping systems have usually been supplied with oiling devices of various kinds, the most common form of pump having a crank case arranged to receive a supply of oil capable of providing lubrication to the crank shaft and connecting rod for a long period of time. Such pumps, however, require special means for segregating the oil from the water passages so as to maintain a pure water supply. Furthermore, it is well known that in spite of warnings and admonitions, the users frequently fail to renew the oil, thus permitting the crank case to run dry, with a consequent sticking or burning out of the main bearings with attendant breakdowns of the pumping system.

In carrying out my invention, I provide an improved form of double acting pump wherein one set of inlet and outlet valves serves a pressure chamber which includes the crank case, thereby causing part of the water to flow through the crank case and provide constant lubrication for the moving parts therein, including the crank shaft, connecting rod and the plunger.

Other features of the invention will appear from time to time as the following description proceeds.

My invention may best be understood by reference to the accompanying drawings, in which

Figure 1 is a transverse section of a pump casing constructed in accordance therewith.

Figure 2 is a partial section taken on line 2—2 of Figure 1.

Figure 3 is a detail view in perspective of the main crank shaft bearing and packing means therefor.

Referring now to details of the embodiment of my invention illustrated in the drawings, the main parts of the pump consist of a cylinder 10, a plunger 11 in said cylinder, a connecting rod 12, a crank arm 13 and a crank shaft 14. Said parts are all preferably mounted and enclosed within a unitary casing 15 with the exception of the shaft 14 which extends through a detachable bearing and packing plug 16 at one side of the crank case 15^a of the pump, as clearly shown in Figure 2.

The cylinder 10 herein consists of a cylindrical sleeve mounted in a centrally disposed support 17 near one end of said casing, said support being formed integrally with a pair of transversely disposed webs 18 and 19 which extend the full width of the main casing 15 and divide the interior of said casing into two chambers 20 and 21, communicating respectively with opposite ends of the cylinder 11. It will be noted that the larger chamber 20 also forms the crank case 15^a or the 10 portion of the main casing 15 which encloses the connecting rod 12 and crank shaft 13.

Each of said chambers is provided with a set of inlet and outlet valves. In the form shown, the inlet valve 20^a associated with the chamber 15 20 and the companion inlet valve 21^a associated with the chamber 21 are both mounted on inner plates 25 and 26 of an inlet casing 27 which is arranged to be detachably connected to one side wall of the main casing 15 so that said plates 25 20 and 26 cover the side openings of the passageways 20 and 21, as clearly shown in Figure 1. Water is admitted to the casing 27 through an inlet 28 at one side of the main casing 15 and communicating with the passage 29 between the 25 adjacent webs 18 and 19, which passage opens laterally into the interior of the inlet casing 27 as clearly shown in Figure 1.

The inlet valves 20^a and 21^a may be of any suitable form, herein being of the poppet type, 30 each including a valve plate 30 adapted to close an aperture 31 in valve seat 32. Said valve plate 30 is slideable on a pin 33, having a head 34 with a coil spring 35 engaged between said head and said valve plate so as to normally maintain the 35 latter in closed position against its seat.

The outlet valves for the chambers 20 and 21 are indicated at 20^b and 20^c, said valves being of the same type as the inlet valve previously described, but herein being mounted on transverse 40 webs 36 and 37 formed integrally with the main casing 15 but on opposite sides of the transverse webs 18 and 19 which separate the chambers 20 and 21 apart as previously described. Said outlet valves communicate with a common pressure 45 chamber 38 formed by a detachable cover 39 which is provided with an outlet opening 40.

The form of plunger 11 shown herein as made up of a longitudinal pin 45 having an eye 46 at one end thereof to which is pivotally connected 50 the yoke 12^a of the connecting rod 12. A sleeve 47 surrounds the pin 45, a collar 50 is mounted on said sleeve, and a pair of washers 48 and 49 are mounted at opposite ends of said collar, said washers being of fiber or leather of the expandible 55

type generally utilized for pump plungers, and secured against the central collar 50 by retaining rings 48^a and 49^a, respectively. The several parts 5 of the plunger are finally secured together by nuts 51 threaded on the end of the pin 45 and engaging the outermost retaining ring 49^a as shown in Figure 1.

Bearing means are provided between the crank arm 13 and crank shaft 12 so as to be particularly effective for lubrication by water. In the 10 form shown, the crank shaft 12 and the crank arm 13 are both designed to be made of brass castings, the crank arm having a sleeve 13^a suitably fixed on the end of crank shaft 14 as by 15 brazing. The connecting rod pin 13^b of the crank arm 13 has a bushing 13^c fixed thereon, said bushing preferably being of rust resisting steel alloy and engaging in a bronze bushing 55 carried by the connecting rod 12. This arrangement 20 gives a steel-to-bronze bearing which is found to be particularly effective in a device of the character described. Suitable lubrication grooves 56, 56 are formed lengthwise the bronze bushing 55 as shown in Figures 1 and 2 so as to permit the 25 flow of water the full width of the connecting rod bearing for lubrication of the same.

Referring now to the bearing for a crank shaft 14 and crank arm hub 13^a mounted thereon, I provide a steel bearing sleeve 57 on said crank 30 arm 13^a which has engagement with a bronze bushing 58 fixed in the inner end of the bearing plug 16 as clearly shown in Figures 2 and 3. Said bronze bushing 58 fits in a recess 59 formed in said bearing plug, but said bushing as well as 35 the hub 13^a and steel bearing sleeve 57 are shorter than the total depth of the recess 59 so as to form a chamber 60 at the inner end of said hub, as clearly shown in Figure 2. A pair of water 40 ducts 61 and 62 are formed adjacent the periphery of the plug 16 so as to afford communication between the opposite sides of the chamber 60 and the interior of the crank case 15^a. Lubrication grooves 63, 63 are also formed on the interior of the bronze bushing 58 and extending 45 longitudinally thereof. The arrangement just described is such that water may circulate through the ducts 61 and 62 and the grooves 63, 63, thus insuring a free and continuous flow of water through the main bearing of the crank shaft at 50 all times.

Also mounted within the bearing plug 16 beyond the chamber 60 is a packing gland 65 closed by a rotatable plug 66 which is reached through oppositely disposed openings 67, 67 formed in said 55 plug. Said bearing plug may also be provided at its outer end with an anti-friction bearing 68 as shown. It will be observed that the entire bearing plug is attachable as a unit to one side of the crank case 15 as by screw threads 16^b en-

gaging a co-operating boss 15^b at one side of the crank case.

In the preferred form of pump casing shown, in which the crank casing is made of integral casting, access to the plunger and connecting rod 5 within the casing is afforded by means of a plug 68 closing one end of the chamber 21 opposite the cylinder 18, and a corresponding plug 69 at the opposite end of the casing and closing the end of the chamber 20 opposite the connecting rod 12. With this arrangement access to the outer end of the plunger may be had through the plug opening 68, while access to the rear end of the plunger and the connecting rod may be had through the plug opening 69. The working parts 15 may be entirely removed from the casing by first unscrewing the bearing plug 16 and removing the crank pin 13^b from the connecting rod, and then removing the connecting rod and plunger endwise through the plug opening 69. 20

With the construction above described, it will now be understood that the pump operates with the usual double action, but that the part of the flow of water through chamber 20 serves to lubricate the moving parts with a constantly changing 25 supply of water, thereby making it unnecessary to provide any auxiliary lubrication to these parts, and assuring a constant flow of pure water at all times.

Although I have illustrated and described a 30 certain embodiment of my invention, it will be understood that I do not wish to be limited to the exact construction shown and described, but that various changes and modifications may be made without departing from the spirit and 35 scope of my invention.

I claim:

In a liquid pump, operating means including a rotating drive shaft and a crank arm thereon, a casing having an opening of sufficient size to 40 permit said shaft and crank arm to pass therethrough, an elongated bearing member forming the sole support for said shaft and detachably connected to said casing to form a closure for said opening, said member having a bore at its 45 inner end coaxial with but of substantially greater diameter than said shaft, an imperforate cylindrical bearing for said shaft adapted to fit in said bore but spaced from the inner end thereof so as to form a chamber at the end of said shaft 50 bearing remote from said casing, said bearing member also having a duct formed therein extending from said casing to said chamber so as to form independent access of lubricant to both ends of said shaft bearing, and said bearing member 55 also having another bearing carried at its outer end, and adjustable packing means interposed between said first and second shaft bearings.

HERBERT R. LAFFERTY.
